ROTARY PUMP OR THE LIKE

Henry G. Bowering, Needham, Mass., assignor to
 Kinney Manufacturing Company, Jamaica
 Plain, Mass., a corporation of Massachusetts

Application January 22, 1938, Serial No. 186,402

9 Claims. (Cl. 103—128)

The invention herein discussed relates to rotary pumps and compressors and the like and is applicable to such devices of various types.

For the purpose of discussion and disclosure, I refer to certain difficulties developed in pump service generally and to their correction. Other features are novel items of improvement in the general art as will be apparent to those skilled in its practices.

Pumping and like equipment according to my invention is intended for various uses and in some installations as on oil tankers, they may be called upon to handle as different materials as cargo gasoline or salt water ballast after unloading. Such uses subject the rotors and associated interior parts to very severe wear requiring frequent replacements. Repairs or replacements must, of course, be made as quickly as possible with a minimum tie-up of the pump on which such a cargo carrier is so dependent.

The handling of gasoline above cited, imposes a most exacting test on the tightness of the pumps. Leakage is not only costly but dangerous to cargo and crew. This has led to serious packing problems. In efforts to keep packings tight, as on the pump shafts, they have been set up to limits which with non-lubricating materials developed serious wear on the shaft and increased leakage until replacement became necessary. In pumps of intermeshing type, the inter-pocket pressures tend to become very great. Efforts have been made to vent such pockets but without satisfactory results and usually with a serious weakening of the rotor blades or teeth.

My invention provides for relief both for pocket pressures or for packings or both. As the strain of the pump shaft increases with its lateral dimensions necessary or desirable for capacity, the matter of bearings becomes critical. Extended bearings, however, add to the complications of repair and replacement so that my invention contemplates new improvements which in large measure solve these conflicting difficulties.

While intended to be illustrative for the purposes of disclosure and discussion, I have shown in the accompanying drawings structures of practical value from both manufacturing and operating aspects.

Fig. 1 is a view in partial central section of a pump and drive in accordance with my invention.

Fig. 2 is a plan view of the same.

Fig. 3 is an end elevation showing the driving side of such equipment.

Fig. 4 is a view of the opposite side showing

the face plate removed to expose the overhung rotors.

Fig. 5 is an edge view of a pair of rotors disassembled.

Fig. 6 is a view of one of the rotor pairs disassembled showing the overhang of the rotor ends.

Fig. 7 is an end view of a pair of end liners for the double casing chambers for the rotors.

Fig. 8 is a face view of a pair of liners for the sides of the casing.

Fig. 9 is an edge view of one of such members.

Fig. 10 is a small general view illustrative of another disposition of a pump with intake and discharge with rotors superimposed.

Fig. 11 is an enlarged section of the pump unit at the left of Fig. 1.

In the form of equipment herein shown I provide a base or bed 1 adapted to be anchored to any stable foundation and carrying an intake casing 20 having flanged intake connections 21 and 22 aligned with each other at its opposite sides, one being shown as closed by a plate 22' in favor of the use of the other opening, although pumps may be designed to utilize both of such intakes.

Mounted on the top of the casing 20 and covering its central upward passage 23 is a double rotor casing 30 having a flanged upwardly directed discharge 40 connecting with the rotor casing interior centrally of its opposite interior rotor chambers 31 and 32.

On one side the casing 30 is formed with an opening inclusive of the chambers 31 and 32 and covered with a removable cover plate 33 so that the interior may be readily accessible for assembling or replacing the rotors without disturbing any packings or shaft bearings on lighter or smaller sizes.

The pair of rotors 50 are preferably of the helical blade and groove type and formed with inclined intermeshing members (Figs. 5 and 6). This, as will later appear, permits their disengagement and withdrawal or replacement through the open side of the casing 30 by simply removing the cover plate 33 in smaller sizes of pumps. On its inner face the cover plate 33 is fitted with inwardly projecting buttons or bosses 34 having shouldered or stepped inner end portions 35.

The rotors 50 are diametrically undercut as at 52 on their outer faces next the plate 33 to a dimension equal to the diameter of the hub at the base of the blades to a suitable depth to receive the buttons or bosses 34 which are stepped or shouldered to register with the correspondingly

stepped or shouldered portions 35 of the rotor ends, thus forming an indirect or labyrinthine joint.

On their opposite faces the rotors 50 are diametrically undercut as at 52 to a dimension equal to the diameter at the base of the blades to a suitable depth to receive oppositely disposed cylindrical buttons or bosses 36 adjustably bolted to a cover plate 57 on the wall of the rotor casing 30 opposite to the cover plate 33.

The buttons or bosses 34 and 36 have sufficient clearance between their outside diameter and the diameter at the base of the blades to prevent these bosses acting as supports for the overhanging ends of the rotors. The projected area of each button, i. e. outside boss diameter times boss length, is subtracted from the total projected area of the rotors, which results in a reduction in projected area of the rotors. This reduction in projected area reduces the amount of shaft deflection and load to be supported by the pump bearings. This is made possible by the fact that the undercutting of the rotor ends as at 52 to a dimension equal to its diameter at the base of the blades 51 (see Fig. 6) leaves the ends of the blades overhanging the central cylindrical portion of the rotor 50 through which the shaft 53 passes. These overhanging ends of the blades 51 have their developed pressures backed up without having actual contact, by the buttons or bosses 36 and 34. These portions fill the otherwise empty concavity at the rotor end and so permit the cutting away of the rotor to the base of the rotor blades until they actually are left overhanging. Thus internal pressures are not bottomed on the rotor surface between the blades, but are bottomed at their end areas by the fixed buttons or bosses 34 and 36 on the casing which can thus take up the internally developed pressures without having any stress or strain develop through the rotor on its shaft or bearings. This permits reductions in the projected load area in very considerable amounts with a considerable saving of power in operation and without increased expense in structures for resisting high pressures.

The rotors 50 are thus overhung at their sides or ends making possible the width of lateral dimension to provide full desired capacity and thus permit of operating at higher pressures at the outlet of the pump.

Each rotor is mounted on a shaft 53 or 53' entered through the back wall of the casing 30 and guarded against leakage by a long packing 54 set up by a split gland 55 by threaded T-shaped swing bolts 56.

As will be understood from consideration of Fig. 11, the boss 36 shown at the right of the figure, has a plurality of functions. Not only does it fill the cavity in the end of the rotor to take up the projected pressure load removed from the rotor shaft by removal of the hub portion of the rotor as above described, but it also serves as the outer wall of the stuffing box for the packing 54, the inner wall of which stuffing box is the sleeve 37 fixed on the shaft 53. The boss 36 is formed with an inwardly turned ring portion 36a which contacts the slightly outwardly turned edge 37a of the sleeve 37 to close the end of the stuffing box adjoining the rotor chamber to separate the packing from the rotor chambers 31-32.

As shown in Fig. 11, the outer ends of the bosses 36 are shouldered as at 36' to receive a collar 38 which is bolted to the cover plate 57 which

in turn is bolted to the casing 30. The collar 38 holds the boss 36 firmly in place with the packing 54 pressed within the stuffing box formed by the boss 36 and sleeve 37 as above described.

It being very important, as previously pointed out, to avoid leakage, as when pumping gasoline or other volatile materials, the tendency has been to set up such packings and stuffing boxes 10 very tight with the result where non-lubricating fluids such as the gasoline above instanced or salt water ballast were pumped, the shafts were rapidly worn.

This difficulty I avoid by drilling or otherwise forming small vents or ducts 56' leading from the end 36a of the boss 36 forming the stuffing box for the packing 54 (Figs. 1 and 11) transversely of the rotor and opening into a chamber 56² which is piped as at 58 to the inlet side 20 whereby the pressures on the packings 54 may be adjustably reduced or neutralized by a valved control to inlet pressure (Figs. 1 and 11) and the packings need not be set up so close as to generate the old excessive wear. The valve 58' 25 controlling the venting of the pipe 58 may be of any desired type, that shown being simply a shut-off valve controlled by a hand wheel (see left of Fig. 11.)

By means of this arrangement, it is possible 30 to avoid the former damaging end pressures on the packing. As will be apparent from Fig. 11, I provide an internal discharge communicating with the labyrinth grooves leading from the rotor chambers between the cut out rotor ends 33 and bosses, this discharge beginning at the inner end of the stuffing box and leading back to the suction side of the pump. Liquid under pressure will pass through the labyrinth grooves and the internal passage or vent 56' to the suction chamber 56² with a continuous drop in pressure throughout the course of the flow. By this means, the hydraulic pressure on the inner end of the packing 54 is reduced, thus overcoming the necessity of maintaining the packing as 40 tight as otherwise would be necessary so that the life of the packing is increased and wear on the shaft decreased.

The rotor shafts 53 are supported according to my invention in bearings externally of the rotor casing and hence need not be disturbed in making repairs or replacements in the pump interior, except in very large sizes of pumps. One of the shafts 53 (see Fig. 1) may be called the main shaft as it is extended through the gear housing 61 for connection through coupling or other means to a source of motive power. The shaft of the companion rotor may be called the auxiliary shaft and is indicated at 53' to distinguish it from the so-called main shaft from which it is driven through the gears 60.

As this type of pump is most efficiently made and operated without actual contact engagement of the rotor surfaces, I provide means for driving the auxiliary rotor shaft by intergearing as by a pair of pinions 60 which transmit from one shaft to the other the power necessary to drive one of the rotors without transmission duty on the blades. The pinions are mounted between bearings in the frame 61, preferably exterior to and independent of the rotor casing 30 but in stable mounting on the pump base.

As such it may be a unit of individual adjustment and easy assembly or replacement in case of accident.

In the frame 61 I can provide high efficiency

bearings such as the roller bearing 62 and radial thrust ball bearings 63. The rotor shaft 53 is suitably coupled to a power drive, regard of course being had for direction of rotation of the rotors.

As shown the casing 61 is indicated as detachably yoked or braced as at 64 to the main casing 30.

While almost any type of rotor can be used within the indicated pumping improvements of my present invention, I have devised a form of angular blade which in rotation permits a maximum period of filling and discharging of the bucketlike channels formed by the blades.

While pumps according to my invention are built with simple unlined casings, in certain types it is extremely desirable to fit the rotor areas of the casing with liners and in the drawings I have shown the pump so fitted in a simple and advantageous manner.

As the matter of clearance for the rotor blades and casing walls is important, I provide for the semi-cylindrical members 31 and 32 of the casing liner members 70 (Fig. 7). These are cylindrically curved externally to conform to the inner face of the casing wall and have an inner bore 71 accurately finished as a cylindrical unit and then divided to give the desired clearance with the rotor blades by being pinned in place, as indicated in Fig. 1.

I also may provide lateral liner members 80 (Figs. 8 and 9) which are accurately turned as discs on a radius R and apertured as at 81 for shaft clearance. By turning to the radius of the chambers of the double rotor casing 30 and simply facing off as at 82 on the chord line X—X coinciding with the plane bisecting the zone of rotor tooth interengagement, I provide for a very accurate and practical lining at the rotor ends (Figs. 7, 8 and 9).

The bosses 34 and 36 have still another function in connection with these end liners 80. As shown in Fig. 11, the bosses 34 and 36 have shoulders 34b and 36b respectively on their outer faces. The liners 80 are slipped over the bosses through their apertures 82 and bear thereon against the shoulders 34b and 36b, being firmly held in place by the bolts fastening the end plates 33 and 57 to the casing 30. The ring 38 bolted to the end plate 57 holds the boss 36 in place.

The disposition of the rotor pair may be vertical or superimposed as shown in Fig. 10 but usually is set up side by side as in Figs. 1 to 4. In the vertical or superimposed form the casing has less tendency to drain and so is advantageous in many installations. As disclosed in Fig. 10, a casing 200 has an intake 201 and delivery 202 from rotors on its shafts 203. Where mounted as a deck pump for tanks in a deep hold, this position is of advantage as not requiring priming of the casing should it become drained when emptying a deep tank which in the case of a cargo like gasoline should not only be emptied but be scavenged as far as possible.

The rotor 50 shown in Fig. 6 is indicated as having five blades 51 but rotors with three blades or four or even more than five are entirely satisfactory depending on the width and diameter of the rotors. It is only necessary that the helix angle at the mean diameter be such that there is at least one angular blade on each rotor acting as a closure in each chamber of the double rotor casing between the inlet and outlet connection of the pump chamber. As before stated, the helical bladed rotor shows an advan-

geously smooth action and is very versatile in its ability to handle fluids of different heaviness or density or specific gravity, viscosity or even pulverulent materials. However, my invention is applicable to pumps of the old gear types and these are greatly improved by my concept of overhang and also my venting of adjacent stuffing boxes or packings.

My ability by my invention to provide external bearings is of great advantage, but my other features are capable of use in pumps having interior bearings. While I prefer for most purposes that all my rotor surfaces have free clearance and be carried on their shafts, I can utilize my interior buttons or bosses on which the rotors are overhung as actual rotor bearings. When used as such the overhanging portion of each rotor is fitted with babbitt or other anti-friction metal inserts.

20 All these and many other modifications in combination and structure will be apparent to those skilled in pump design from the illustration and instruction herein given. In the claims, for the sake of brevity, I have referred to my devices as pumps, but it will be understood that this is meant to be a term generally inclusive of pumping and compressive devices.

What I therefore claim and desire to secure by Letters Patent is:

30 1. A pump of the class described comprising a double rotor casing having inlet and outlet passages and intersecting chambers communicating with said passages, intermeshing bladed rotors in said chambers, a shaft for each rotor extending through said casing, each of said rotors comprising a hub and a plurality of blades extending from said hub, the hub portions at the end of said rotors being removed to reduce the projected load area carried by the rotor shafts and to leave cavities over which the ends of said blades overhang, removable end plates secured to said casing, at least one of said plates being outwardly spaced from said rotor ends to provide a suction chamber, bosses rigidly connected to and projecting inwardly from said end plates and extending into said cavities at the rotor ends beneath said overhanging blades to receive the projected load removed from the rotor shafts by the removal of the hub ends and with the walls of said cavities providing grooves leading from said chambers, means defining with one of said bosses a stuffing box, a packing in said stuffing box about one of said shafts, and means leading from said grooves to said suction chamber and to the suction intake of the pump whereby pressures escaping from the rotor chambers past said boss are diverted from said packing.

60 2. The pump of claim 1, the means leading from said grooves to the suction intake of the pump comprising a passage extending transversely through said rotor.

65 3. A pump of the class described comprising a double rotor casing having inlet and outlet passages and intersecting chambers communicating with said passages, intermeshing bladed rotors in said chambers, a shaft for each rotor extending through said casing, each of said rotors comprising a hub and a plurality of blades extending from said hub, the hub portions at the end of said rotors being removed to reduce the projected load area carried by the rotor shafts and to leave cavities over which the ends of said blades overhang, removable end plates outwardly spaced from said rotor ends and secured to said casing,

bosses projecting inwardly from said end plates and extending into said cavities to receive the projected load removed from the rotor shafts by removal of said hub portions, said cavities and said bosses being similarly stepped and shouldered to provide labyrinth grooves leading from said rotor chamber, means defining with one of said bosses a stuffing box, a packing in said stuffing box, and means communicating with said labyrinth grooves and with the suction side of the pump whereby pressures escaping from the rotor chamber through said grooves are diverted from said packing.

4. The pump of claim 3, the means communicating with the labyrinth grooves and with the suction side of the pump comprising lateral passages extending transversely through the rotors.

5. A pump of the class described comprising a double rotor casing having inlet and outlet passages and intersecting chambers communicating with said passages, intermeshing bladed rotors in said chambers, a shaft for each rotor extending through said casing, each of said rotors comprising a hub and a plurality of blades extending from said hub, removable end plates outwardly spaced from said rotor ends and secured to said casing, bosses projecting inwardly from said end plates, said hub ends and bosses being interengaged to provide labyrinth grooves leading from said rotor chamber, means on at least one of said shafts defining with one of said bosses a stuffing box, a packing in said stuffing box, and a passage communicating with said labyrinth grooves and one of said hub ends and extending transversely through said rotor from the end of said stuffing box to the suction side of the pump whereby pressures escaping from the rotor chamber through said grooves are diverted from said packing.

6. A pump of the class described comprising a double rotor casing having inlet and outlet passages and intersecting chambers communicating with said passages, intermeshing bladed rotors in said chambers, a shaft for each rotor extending through said casing, each of said rotors comprising a hub and a plurality of blades extending from said hub, removable end plates outwardly spaced from said rotor ends and secured to said casing, bosses projecting inwardly from said end plates, said hub ends and bosses being interengaged to provide labyrinth grooves leading from

said rotor chamber, a packing on each shaft and spaced from said rotor chamber by one of said bosses, and a passage communicating with said grooves and extending from the chamber side of said last named boss and a conduit from said chamber to the suction intake of the pump whereby pressures escaping from the rotor chamber through said labyrinth grooves are diverted from said packing.

10 7. The pump of claim 5 and liners between said rotors and end plates and mounted on said bosses, one of said bosses including means spacing the liner mounted thereon from the adjacent rotor end to provide a suction chamber intermediate said passage and the suction side of the pump.

20 8. A pump comprising a casing, a rotor having a hub in said casing, a shaft for said rotor entrant through one side of said casing, said casing having a pair of boss portions, said boss portions and the ends of said hub being formed with complementary surfaces defining labyrinth grooves, a shaft packing exteriorly of the complementary surfaces adjacent the shaft entering side of said casing, the opposite side of said casing having an annular recess to receive the other end of said hub and defining therewith a chamber for leakage through the adjacent groove, transverse bores through said hub effecting communication between said chamber and the other groove, and a conduit in communication with said chamber and the suction side of said pump to effect the positive withdrawal of leakage and the like away from said packing.

30 9. A pump comprising a casing, a rotor having a hub in said casing, a shaft for said rotor, a pair of bosses carried by said casing, said bosses and said hub being formed with complementary surfaces defining labyrinth grooves, a shaft packing exteriorly of the complementary surfaces defined by one of said bosses and one end of said hub, the other of said bosses defining with the other end of said hub a chamber, transverse bores through said hub effecting communication between said chamber and said first named boss, and a conduit in communication with said chamber and the suction side of said pump to draw positively leakage and the like away from said packing.

50

HENRY G. BOWERING.
